UNITED STATES PATENT OFFICE

149,979

DESIGN FOR A PLANT CONTAINER OR SIMILAR ARTICLE

Usher Solstone, Los Angeles, Calif.

Application December 23, 1946, Serial No. 135,727

Term of patent 7 years

(Cl. D35—3)

To all whom it may concern:

Be it known that I, Usher Solstone, a citizen of the United States and resident of the city of Los Angeles, county of Los Angeles, and State of California, have invented a new, original, and ornamental Design for Plant Container or Similar Article, of which the following is a specification, reference being had to the accompanying drawings, forming part thereof, in which:

Fig. 1 is a perspective view;

Fig. 2 is a front elevational view; and

Fig. 3 is a side elevational view of a plant container or similar article showing my new design.

I claim:

The ornamental design for a plant container or similar article, as shown.

USHER SOLSTONE.
